UNITED STATES PATENT OFFICE.

FRANCIS ALOYSIUS MONAHAN, OF LONDON, ENGLAND.

DRESS FORM OR STAND.

1,073,157.

Specification of Letters Patent. Patented Sept. 16, 1913.

Application filed June 9, 1911. Serial No. 632,223.

To all whom it may concern:

Be it known that I, FRANCIS ALOYSIUS MONAHAN, a citizen of the United States of America, residing at 102 Oxford street, 5 London, W., England, manufacturer, have invented certain new and useful Improvements in and Relating to Dress Forms or Stands, of which the following is a specification.

- 10 This invention relates to dress forms or stands and has for its object to provide a form or stand upon which the material of which a garment is to be made can be fitted and adjusted into the exact position 15 in which the respective parts are to be sewn and secured together to form the finished garment and it has for its especial objects to provide simple and effective means for fixing the position of the material or parts 20 with reference to the neck, arm and waist so that the fitting shall be exact and the liability to error through the mere pinning of the parts to the form or model shall be avoided, and also to provide means to permit 25 of the arm, neck and skirt parts of garments to be mounted, fitted and loosely sewn or otherwise connected with the bust or bodice part in the position that these parts will assume in the finished garment. 30 According to the invention in the provision of a model or form for a blouse or bodice or coat I provide the form or model of the bust with holes or recesses at the neck and at the side in position corresponding 35 to the arm scye in the garment so that thus the material or constituent parts of which the garment is to be formed may be gathered into these holes and there fixed by suitable means. 40 According to the invention moreover I provide a center part forming the neck of the form or model separate from the bust model proper and so formed as to fit within the recess provided as described and similarly 45 I provide an arm hole blank or block to fit into the recess provided at each side of the bust form or model of a shape corresponding to the arm scye and so formed as to fit closely within the recess provided 50 in the bust model or form so that thus the material at the upper end of the figure or of the parts, when gathered into the neck and arm holes provided as described, may be firmly secured in position by the center neck 55 piece referred to and by the arm hole blanks or blocks respectively.

According to the invention, moreover, I may provide the arm hole blanks or blocks of such form that the arm parts of the garment may be secured to them and on their introduction into position in the arm hole of the bust model or form they may be loosely sewn or otherwise connected together in the relation in which the arm parts assume with reference to the body 60 part in the finished garment.

According to the invention, also, I may provide the arm hole blocks in two parts, one part fitting within the recess provided to receive it in the bust model and having 70 for its purpose to secure the edges of the respective parts of the blouse or bodice in position therein, while the other part or sleeve form is designed to be fitted over the first part and to be of a shape symmetrical 75 with or corresponding to the first part and has for its purpose to serve as a form for and to carry the upper part of the sleeve so that thus the sleeve may be formed, fitted and placed in proper position with reference 80 to the bodice or blouse.

According to the invention the neck block may be similarly provided with a neck form, consisting of a block of suitable shape around the periphery of which felt or other material may be secured, upon which the neck band or part of the garment may be formed and fitted, so that on the application of the neck form to the bust form the neck band will come to lie in its proper 85 position with reference to the bodice or blouse, for temporary connection therewith or by stitching.

According to the invention, also, the lower part of the bust form and upper part of the 90 skirt form may be recessed to receive the inwardly gathered edges of the material of the bodice or skirt, which may be retained in position by means of blocks or by applying the bust form upon the skirt form.

The application of the invention is illustrated, by way of example, in the accompanying drawings in which

Figure 1 is a perspective view of the form parts assembled together. Fig. 2 is a perspective view, on an enlarged scale, of an arm hole in the bust model or form. Fig. 3 is a perspective view, on an enlarged scale, of one of the arm blocks and the corresponding sleeve form. Fig. 4 is a perspective view, on an enlarged scale, of the upper part of the bust form or model showing the neck

recess. Fig. 5 is a perspective view, on an enlarged scale, of the neck block and neck form. Fig. 6 is an elevation, on an enlarged scale, of the sleeve form device with the sleeve form in position. Fig. 7 is an elevation, partly in section, corresponding to Fig. 6, taken at right angles thereto. Fig. 8 is a part elevation on an enlarged scale, of the bust form or model showing the recessed lower part. Fig. 9 is a part elevation, on an enlarged scale, of the skirt form or model showing the recessed upper part.

In carrying the invention into effect, as illustrated in the drawings, I advantageously provide a bust stand or form *a* of any suitable material as usually employed, for example, such as papier mâché or similar material covered over with cloth or sateen or not as may be required and I provide in the bust model or form a central recess *b* whose peripheral edge corresponds to the lower part of the neck and with lateral recesses *c* corresponding to the arm scyes. I provide a center or neck block *b*¹ having upon the under side pegs *e* adapted to pass into corresponding holes *e*¹ formed within the neck recess *b* so that when the block *b*¹ is introduced in position in the neck recess it may be retained therein.

I may provide the recess *b* of the neck in the bust form or model lined with metal or some other durable substance or material.

The arm hole recesses *c* in the bust model or form *a* are similarly formed and may also be provided with a metallic lining or a lining of some other durable substance or material. They are provided with one, two or more holes *e*² into which corresponding pegs *e*² may enter that are provided upon the respective arm hole blocks *c*¹ so that thus each block may be placed exactly in its position within its recess.

The neck block *b*¹ and the arm hole blocks *c*¹ may have their peripheries or faces covered with felt or other material, by means of which material forming the neck band or arm part of the garment may be pinned or otherwise secured to it in the position it will assume for being secured to the bust part of the garment.

The sleeve form *c*² is advantageously provided with pegs *d* to pass into corresponding holes *d*¹ formed in the arm hole block *c*¹ which is fitted in the arm hole recess *c* within the bust model itself, and the same pegs or other means for mounting the sleeve form *c*² in position upon the bust model may be used for applying the sleeve form upon a sleeve form device or bracket, which has for its purpose properly to form and fit the upper part of the sleeve. The sleeve form *c*² is capable of ready withdrawal from the sleeve form device with the sleeve formed or fitted upon it and of being readily applied in position upon the bust model or form *a*,

the sleeve being applied in the position in which it may be connected temporarily as by stitching to the arm scye of the bodice or blouse already fitted upon the bust model or form.

In carrying this part of the invention into effect I provide a bracket *f*¹, which may be fixed on a stand or upon the wall or in any other suitable position and carrying a block *f* roughly formed of a shape corresponding to the shape of an arm hole. This block *f* may be made in a series of standard sizes and provided with felt around its periphery for convenience in pinning or otherwise temporarily mounting or securing the sleeve in position thereon. This block *f* is also formed with one or more holes *d*² within it for the reception of the pegs *d* provided upon the sleeve form *c*², which is provided with a periphery symmetrical with or corresponding to that of the block *f* and may also be made in a series of standard sizes. The sleeve form is provided of a shape suitable for forming the upper part of the sleeve. The sleeve is shaped upon the sleeve form *c*² and upon the block *f* and after it has been suitably fitted and secured to the sleeve form it is applied in position upon the bust model. The bodice or blouse which is already in position upon the bust model has the edge of the arm scye suitably gathered into the arm hole recess *c* of the bust model, and the arm hole block *c*¹ is fitted so as to secure the edges in position therein. The sleeve form *c*² carrying the sleeve is then mounted in position, the pegs *d* passing through the holes *d*¹ *d*² provided respectively in the arm hole block *c*¹ and in the bust form *a* for the purpose of the fitting and connection of the sleeve in proper position to the bodice or blouse. In a similar manner a neck form *b*² may be provided as a block of any suitable shape and depth, advantageously covered in felt or similar material and provided with pegs *h* to pass into holes *h*¹ *h*² formed respectively in the neck block and bust form, to retain it in position during the connection of the neck band to the bodice or blouse.

The sleeve form, neck block and arm hole blocks are each advantageously provided with two recesses *g* leaving a central part *g*¹ by which it may be conveniently handled.

As shown in Figs. 8 and 9 of the accompanying drawings the lower part of the blouse or bodice may be gathered into position within a recess *a*¹ provided on the waist line under the bust model or form *a*, while a skirt form or model *i* is also provided having means to gather the upper edges of the skirt parts into a recess *i*¹ formed on the top of the skirt form or model on the waist line.

Blocks may be provided for mounting beneath the bust form, or upon the skirt form,

in the manner hereinbefore described by means of which the edges of the respective parts of the garment may be retained in position for fitting, or instead the bust and skirt forms may be mounted one upon the other as shown in the drawing, pegs i^2 being advantageously provided on the top part of the skirt model or form i to fit into corresponding holes a^2 provided in determined position in the bottom of the bust model or form, so as thus to dispense with the necessity of separate blocks for retaining the edges of the respective garments in position.

15 It will be understood that the invention is of general application to models, forms or stands employed for the purpose of fitting garments or for adjusting the respective parts together in fixed relation to form the garment.

Again, the invention is not limited to the material of which the model or form is made for it may be made of any material other than that specified, for example, the bust model may be made of wire or partly of wire and the arm and neck parts may be formed of metal to permit of the reception of the center neck part and the arm hole blanks or blocks referred to.

30 It will be also understood that the invention is not limited to the use of such means as pegs for retaining the parts in relative position. For example, the neck block may be provided with an under or spigot part 35 having a slightly tapered periphery so that on the introduction of the neck block into the neck recess it may be retained therein by friction.

Any means may be provided for securing 40 the material to form the garment in position upon the model.

What I claim as my invention and desire to secure by Letters Patent is:—

1. A dress form or stand having recesses 45 at the neck and arms in which the edges of the material of the garment on the form or stand are gathered, blocks fitting into said recesses and corresponding in shape thereto and retaining the edges of the said material 50 therein.

2. A dress form or stand having recesses at the neck and arms in which the edges of the material of the garment on the form or stand are gathered, blocks fitting into said 55 recesses and members on which other parts of the garment are formed, said members being adapted to fit on said blocks.

3. A dress form or stand having recesses

at the arms in which the edges of the material of the garment on the form or stand 60 adjacent the arms are gathered, and blocks fitting into said recesses and of a shape corresponding thereto, by which the edges of the material of the garment adjacent the arms may be retained within the recesses by 65 the blocks aforesaid.

4. A dress form or stand having recesses at the arms in which the edges of the material of the garment on the form or stand 70 adjacent the arms are gathered, blocks fitting into said recesses, pegs upon the blocks for entry within corresponding holes at the bottom of the recesses and for mounting the said blocks in proper position within the 75 said recesses.

5. A dress form or stand having recesses at the arms in which the edges of the material of the garment on the form or stand 80 adjacent the arms are gathered, blocks fitting into said recesses and corresponding in shape thereto, and blocks on which the sleeve parts of the garment are formed, and means for mounting the said blocks last referred to in proper position on the said dress 85 form or stand.

6. A dress form or stand having recesses at the arms in which the edges of the material of the garment on the form or stand 90 adjacent the arms are gathered, blocks fitting into said recesses and corresponding in shape thereto, and blocks upon which the sleeve parts of the garment are formed, pegs carried thereby by which the said blocks last referred to may be applied in proper 95 position upon the dress form or stand.

7. A bust form having recesses at the arms in which the edges of the material of the garment on the form or stand adjacent the arms are gathered, blocks fitting into said recesses and of a shape corresponding 100 thereto, by which the edges of the material of the garment adjacent the arms may be retained within the recesses by the blocks aforesaid, a skirt form upon which said bust form is mounted and means for mounting the said bust form in proper position 105 upon the said skirt form, and a recess on the lower part of said bust form in which the edges of the garment may be gathered.

In testimony whereof I have hereunto 110 signed my name to this specification in the presence of two subscribing witnesses.

FRANCIS ALOYSIUS MONAHAN.
